UNITED STATES PATENT OFFICE

2,547,688

MOTH-REPELLENT CAKE AND A CONTAINER
THEREFORDavid Brody, Clinton, Mass., assignor to Van
Brode Milling Co., Inc., Clinton, Mass., a cor-
poration of Massachusetts

Application March 25, 1950, Serial No. 151,867

2 Claims. (Cl. 299—24)

1

The present invention relates to improvements in containers especially adapted for receiving moth-repellent material, in the form of cakes, and pertains also to improvements in the cakes themselves.

Cakes of moth-repellent material are, for purposes of transportation and storage, usually wrapped and properly sealed in sheet material impervious to air, for instance, "cellophane." In use, a cake, after having the wrapper removed therefrom, is placed into a suitably perforated container or box, to expose the moth-repellent substance to the action of air.

In the act of removing the wrapper from the cake, the hands of the user, obviously, come into contact with the moth-repellent material, whereby some of the moth-repellent adheres to the hands. Although the bulk of the repellent adhering to the hands is capable of being removed by washing and scrubbing, a thin film invariably stays on the hands and imparts a rather unpleasant odor to the same. This odor lingers until the said film has fully evaporated.

The primary object of the present invention is to so construct and arrange the container and cake that the moth-repellent substance is adapted to be exposed without necessitating contact between said substance and the hands of the user.

Another object of the invention is to provide a container of the type mentioned, which is very simple in construction, extremely efficient in operation, and which is capable of manufacture on a commercial scale or, in other words, one which is not so difficult to produce as to be beyond the reasonable cost of such an article.

Other objects and advantages of this invention will be apparent during the course of the following detailed description.

One of the many possible embodiments of the present invention is illustrated in the accompanying drawings, in which:

Figure 1 is a front elevation of the improved container with the improved moth-repellent cake positioned therein; and

Figure 2 is a section taken on line 2—2 of Figure 1, on an enlarged scale.

The container comprises a body portion 10 and a closure portion 11. The body portion, consisting of a cylindrical wall 12 and a flat end 13, is made of a suitable stiff or rigid plastic material of a type that is resistant to corrosion or attack by the moth-repellent mass which is to be placed into the container. The closure portion is disk-shaped and provided on its inner face 14 with an annular flange 15, fitting tightly the mouth 16

2

of the container, the peripheral section 17 of the closure being adapted to overlie the mouth-rim 18 of the container. The closure material, preferably, comprises the polymers of ethylene known under the trade-names "Polithene" and "Polyethylene." These are rubber-like thermoplastic compositions; have flexibility and elasticity; and are frictional. They are not corroded, nor attacked by the usually employed moth-repellent materials.

For the application of the closure to the body portion of the container, the flange of the former is placed over the mouth of the body portion and the closure pressed toward said body portion, whereby said flange is forced into the latter, the closure being retained by friction on the container. The flange being elastic, it is obvious that the closure will adjust itself to slight variations in the size of the mouth of the body portion.

In the flat end 13 of the container body portion and in the closure disk are formed centrally disposed registering apertures 19 and 20, respectively.

The moth-repellent cake, denoted by the numeral 21, is disk-shaped to fit the container above described, and has formed therein a central hole 22, capable of coinciding with the apertures in the two portions of the container. The cake is provided with a sealing wrapper 23, which is impervious to air. "Cellophane" is especially suited for a wrapping material for the purposes of this invention.

Around its hole 20, the closure disk has formed on its inner face a bead 24, which serves to impart the desired strength to the closure in the region of its hole.

Means are provided for suspending the container. The suspending element herein disclosed is in the form of a hook 25, which may be attached to or made integral with the body portion 10.

To place a cake into the container, the two elements of the latter are first taken apart. For this purpose, the closure is grasped at a point of its peripheral section and easily and expeditiously peeled from the body portion of the container. The cake, enclosed in its wrapper, is then placed into the body portion. Finally, the closure portion of the container is assembled with the body portion 10 and the cake. In the assembled state, the apertures in the container are in alignment with the hole in the cake.

After the elements have thus been assembled, the cake wrapper is ruptured by means of an instrument thrust through the registering apertures and hole in the container and cake,

respectively. The moth-repellent material is thereby exposed to the action of air, the material thus being caused to evaporate. The vapors escape into and fill the closed space in which the device is mounted.

It is obvious that, while herein a container of a specific shape has been described, others may be made use of without departing from the invention, which lies mainly in the provision of a closed container and a moth-repellent cake within a sealing wrapper fitted into said container, the cake and container being provided with holes in registering positions, whereby the wrapper may be pierced by a suitable instrument after the elements of the device have been assembled.

What I claim is:

1. An article of manufacture for repelling moths, comprising a container including a body portion and a closure portion, a flange of elastic material on said closure portion fitting into the mouth of said body portion for retaining said closure by friction on said body portion, said container portions having centrally disposed registering apertures, and a cake of moth-repellent material enclosed in a sealing wrapper which is impervious to air fitted into said con-

tainer, said cake being provided with a hole in alignment with said apertures, whereby said wrapper is adapted to be ruptured by an instrument thrust through said registering apertures and hole to expose the moth-repellent material to the action of the surrounding air.

2. An article of manufacture for repelling moths, comprising a container including a body portion and a closure portion, said portions having centrally disposed registering apertures, and a cake of moth-repellent material enclosed in a sealing wrapper which is impervious to air fitted into said container, said cake being provided with a hole in alignment with said apertures, whereby said wrapper is adapted to be ruptured by an instrument thrust through said registering apertures and hole to expose the moth-repellent material to the action of the surrounding air.
